UNITED STATES PATENT OFFICE.

DWIGHT SAMPSON, OF ADRIAN, MICHIGAN, ASSIGNOR TO SCHWARZE ELECTRIC COMPANY, OF ADRIAN, MICHIGAN, A CORPORATION OF MICHIGAN.

DIAPHRAGM ACTUATING STUD FOR SOUND PRODUCERS.

Application filed November 20, 1920. Serial No. 425,366.

To all whom it may concern:

Be it known that I, DWIGHT SAMPSON, a citizen of the United States of America, residing at Adrian, in the county of Lenawee 5 and State of Michigan, have invented certain new and useful Improvements in Diaphragm Actuating Studs for Sound Producers, of which the following is a specification, reference being had therein to the accompanying drawings.

The invention relates to sound producers for signaling horns of that type in which a flexible diaphragm is thrown into vibration by a mechanical agitating member engaging 15 a stud or pin at the center of the diaphragm. It is the object of the present invention to form a simple construction of actuating stud which is easily applicable to the diaphragm and is adapted for cooperation 20 with the actuating member.

In the drawings:

Figure 1 is a cross-section through a diaphragm having the actuating stud secured thereto;

Figure 2 is a similar view showing the actuating stud applied to a corrugated diaphragm;

Figure 3 is an enlarged perspective view of the stud member.

A is the diaphragm which in Figure 1 is shown as plane and Figure 2 as corrugated. B is a small disk having a tongue C struck out from the central portion thereof and also provided with apertures D for the passage 30 of rivets or other devices for fastening to the disk. In securing the member B to the diaphragm, a reinforcing disk E of corresponding size is preferably placed on the opposite side of the diaphragm and rivets F 35 are then passed through the two disks and

intervening diaphragm to secure the same together. The tongue C is preferably inclined as shown and is adapted for cooperation with a toothed actuating member (not shown).

One advantage of my construction is that there is no danger of the actuating stud becoming disengaged from the diaphragm or tearing or otherwise engaging said diaphragm when in use. Another advantage is 50 that the device may be formed by stamping at small cost and it is easily applied.

What I claim as my invention is:

1. The combination with a vibratory diaphragm, of an actuating member therefor 55 comprising a flat portion in a plane parallel to the diaphragm, a tongue struck out from the center of said portion, and means for securing the parallel portion of the diaphragm.

2. The combination with a vibratory diaphragm, of an actuating member therefor comprising a disk having a tongue portion struck out therefrom, and means for securing said disk to the diaphragm.

3. The combination with a vibratory diaphragm, of an actuating member therefor comprising a disk having an obliquely-arranged tongue struck out therefrom, and means for securing said disk to the diaphragm.

4. The combination with a vibratory diaphragm, of an actuating member therefor comprising a flat member, a tongue struck out from the center of said member, and 75 means for securing said member to the diaphragm.

In testimony whereof I affix my signature.

DWIGHT SAMPSON.
